ASSEMBLING MACHINE

Herbert E. Edwards, Brookline, Mass.

Application July 6, 1931, Serial No. 548,745

28 Claims. (Cl. 12--52)

The present invention relates to assembling machines, and more particularly to machines for assembling component parts of shoe uppers.

In the manufacture of shoes, particularly for women, it is necessary to assemble with shoe upper parts, such as vamps, tips and quarters, relatively small pieces such as overlays and underlays. In addition it is customary to reinforce inherently weak portions of the shoe upper parts or portions thereof which will be weakened in subsequent operations by applying locally relatively small staying or reinforcing pieces. The application of these relatively small pieces to a particular portion of the shoe upper part is expensive as it involves a number of operations most of which must be performed by hand with skill and care. First the shoe upper part must be marked to indicate accurately the portion thereof which is to receive the small piece, whether it is an overlay, underlay or a reinforcement. Then one face of the small piece must be rendered sticky, either by treating a prepared coating thereon or by applying adhesive thereto. Then the sticky piece must be superimposed upon the shoe upper part, care being taken to cover the proper portion of the shoe upper part by registering the piece with the mark previously formed on the shoe upper part. Finally the assembled parts must be subjected to pressure to insure the adherence of the superimposed piece to the underlying shoe upper part.

The object of the present invention is to produce a machine which will assemble unmarked component shoe upper parts in a rapid, reliable and inexpensive manner.

To the accomplishment of this object, and such others as may appear hereinafter, the various features of the present invention consist in certain constructions, combinations and arrangements of parts hereinafter described and then set forth broadly and in detail in the appended claims.

The various features of the present invention will be understood readily from an inspection of the accompanying drawings, illustrating the best form of the invention at present devised, in which,

Figure 1 is a view in plan of the assembling machine, the pick-up means being at the pick-up station;

Fig. 2 is a view in front elevation;

Fig. 3 is a view in plan, the pick-up means being at the superimposing station;

Fig. 4 is a view in sectional elevation on the line 4—4, Fig. 3;

Fig. 5 is a view in plan illustrating a modification;

Fig. 6 is a view in elevation of the modified type of die illustrated in Fig. 5;

Fig. 7 is a detail view in sectional elevation of the roll for rendering the bottom faces of the pieces of stock adhesive;

Fig. 8 is a detail view in sectional elevation illustrating the mechanism for lowering the roll during the idle stroke of the dies, and

Fig. 9 is a detail view in rear elevation of the mechanism for lowering the disappearing pins in a step by step manner.

In the embodiment of the invention illustrated in Figs. 1, 2, 3 and 4, the machine is set up to support separately a pair of shoe upper parts herein shown as quarters 10, one right and the other left (Fig. 1), and a pair of stacks 11 (Fig. 2) of pieces of stock 12 (Figs. 1 and 3) herein shown as stays for reinforcing the quarters 10 in the region of the eyelet holes to be inserted therethrough in a subsequent operation.

The quarters 10 are supported flat-wise upon the horizontal surface of a pattern 13 which is provided with one or more holes 14, herein shown as four in number. The holes 14 receive vertical pins 15 projecting upwardly from the flat top of an elevated bed 16 integral with a bed plate 17. With this construction the pattern 13 is removably mounted on the bed 16.

The stacks 11 are supported upon a pattern 18. For economy in manufacture the patterns 13 and 18 are standardized. The pattern 18 is provided with holes 19 which receive vertical pins 20 projecting upwardly from the upper walls of a hollow bed 21 on the bed plate 17. The walls of the hollow bed 21 form a box-like structure which is closed at its top by the pattern 18. The pattern 18 is provided with a plurality of eyelets 22 (Fig. 3) which embrace loosely a plurality of pins

23 (Figs. 3 and 4) which confine laterally the pieces 12 in the stacks 11 in all directions by engagement with various points on their edges. The stacks are thus supported in magazines each having a stationary bottom and a vertically movable retaining wall. The bottom of the pattern 18 is reinforced in the region of the eyelets 22 by a backing plate 24 (Fig. 4). The bottom ends of the pins 23 are supported by a false bottom 25 the edges of which engage loosely the internal walls of the hollow bed 21. The false bottom 25 rests on a horizontal plate 26. With this construction the location of the eyelets 22 may be varied as desired to change the shape or size of the area bounded by the pins 23. Provided the

50

55

eyelets 22 are properly located, the operative may 5 prepare the pattern 18 for the support of work pieces 12 varying widely in size or shape merely by dropping the pins 23 through the eyelets as the bottoms of the pins 23 may rest upon any portion of the extensive surface of the false bottom 25.

Soldered to the bottom of the plate 23 are two horizontal rods 27 and 28 which are wider than the plate so that the ends thereof may project 10 into inclined slots 29 and 30, respectively, formed in the lateral side walls of the hollow bed 21. Pivoted to the horizontal rod 28 are two links 31 and 32 (Figs. 3 and 4) which are pivoted, respectively, on pins 33 and 34 carried by ears 35 and 15 36 projecting upwardly from a slide 37 mounted to slide on the bed plate 17. Secured centrally to the slide 37 is a strap 38 which carries on its free end a roll 39 (Figs. 1, 3, 4 and 9) arranged to engage the peripheral edge of a verge 40. 20 The verge 40 is carried by a ratchet 41 rotatably mounted on the cylindrical shank of a horizontal bolt 42 (Fig. 9). The shank of the bolt 42 is threaded on both ends to receive nuts 43 (Fig. 4) and 44 (Fig. 9) one of which, the nut 43, secures 25 the bolt to the rear wall of the hollow bed 21. The bolt 44 holds the verge 40 and the ratchet 41 in position on the shank of the bolt 42. The roll 39 is held in engagement with the verge 40 by a pair of coiled springs 45 (Fig. 3) the ends of each 30 of which are secured to the horizontal rod 28 and to pins 46 projecting laterally from the side walls of the hollow bed 21.

Shoe factory systems vary in the number of pairs constituting a case lot. In some factories 35 thirty-six pairs form a case lot. In others, twenty-four. In still others, twelve. The pins 23 (Fig. 4) are standardized. That is, they are long enough for use with a stack 11 formed by thirty-six of the pieces 12. When a stack 11, containing less than thirty-six pieces of stock, is to be 40 supported upon the pattern 18, the distance the pins 23 project above the work supporting surface of the pattern 18 is reduced so that the upper ends of the pins 23 may project above the top 45 piece of stock in the stack a predetermined distance, the amount of which is uniform for all heights of stacks and which is maintained uniform as the pieces of stock are withdrawn one at a time from the stack.

To enable the operative to adjust the pins 23 preliminarily to accommodate them to different heights of stacks 11 the shank of the bolt 42 carries loosely an arm 47 (Fig. 9). Normally the arm 47 is held against a pin 48, projecting from the rear wall of the hollow bed 21, by a coiled spring 49 one end of which is secured to the rear wall of the hollow bed 21 and the other end of which is secured to a bent pin 50 secured to the arm 47. The arm 47 carries a pivoted spring pressed pawl 51 arranged to engage the ratchet 41. The operative may, by oscillating the arm 47, operate the ratchet 41 in a counter-clockwise direction, viewing Fig. 9, through the pawl 51, and thus rotate the verge 40. The verge 40 by engagement with the roll 39 draws the slide 37 to the right (Fig. 4) thus causing the rods 27 and 28 to travel down the slots 29 and 30 and lower the plate 23 which supports the false bottom 25 upon which the pins 23 rest. The ratchet 41 is held from a retrograde 60 movement, viewing Fig. 9, by a pivoted spring pressed pawl 52 mounted in a cage 53 secured to the rear wall of the hollow bed 21.

In order to withdraw the uppermost piece from 65 both of the stacks 11 simultaneously the pieces 70 75 are engaged, respectively, by dies 54 and 55 (Fig.

2) projecting downwardly from the bottom face of a flat plate 56 removably secured to a holder 57. To this end the plate 56 is provided with a pair of upstanding pins 58 which are received in holes formed in the holder 57. The pins 58 near their upper ends are provided with notches engaged by latches 59 pivotally mounted on the holder. By swinging the latches 59 on their pivots the pins 58 are released so that the plate 56 may be withdrawn from the holder 57 and another 10 plate 56 carrying other dies 54 and 55 substituted therefor.

The dies 54 and 55 have flat bottom faces shaped in exact accordance with the shape of the pieces in the stacks 11. The dies project below 15 the bottom of the plate 56 a distance commensurate with the distance the pins 23 project above the uppermost pieces in the stacks 11. With this construction the dies enter into the spaces defined by the pins 23 to engage the uppermost pieces 20 in the stacks, the extent of this movement being limited by the upper ends of the pins 23 which engage the plate 56.

The holder 57 is carried by the bottom of a rod 60 (Fig. 4) which slides vertically in a boss 25 61 formed in a head 62. The head 62 receives and slides upon two horizontal rods 63 and 64 the free ends of which are supported, respectively, in brackets 65 and 66 projecting upwardly 30 from the bed plate 17. With this construction the head 62 is constrained to slide laterally in a single horizontal plane.

In order to reciprocate the rod 60 to lower the dies 54 and 55 into engagement with the top pieces in the stacks 12, the rod is slotted to 35 receive an arm 67 pivoted at one end on the head 62 and provided on its other end with an operating handle 68. The arm 67 and the parts operated thereby are held normally in the position of Fig. 4 by a coiled spring 69 which is mounted in a spring chamber 70 formed in the head 62. The upper end of the spring 69 engages a pin 71 depending from the arm 67.

In order to constrain the downward movement of the rod 60 to a single vertical plane the 45 horizontal rod 63 is provided with an opening 72 (Fig. 3) which, when the head 62 is positioned against a buffer 73 on the rod 63, is in position to receive a pin 74 mounted in an opening 75 formed in the head 62. The upper end of the pin 74 50 is pivoted between two plates 76 (Figs. 1 and 4) which are secured to the opposite sides of the arm 67.

In order to prepare for the operation of the 55 machine the pattern maker designs paper patterns having contours identical with the shoe upper parts to be supported upon the pattern 18. Each paper pattern has an opening cut therein having a contour identical with the pieces to be supported upon the pattern 18. Thus the paper 60 patterns show not only the contours of the left and right shoe upper parts and the pieces to be superimposed thereon, but the exact position the pieces should occupy when superimposed upon the shoe upper parts.

With these paper patterns as guides, the dies 54 and 55, on the bottom of the plate 56, are 65 constructed with surface contours identical with the openings in the paper patterns. Stated in another way, the dies 54 and 55 are provided 70 with contours on their bottom faces, respectively, identical with the contour of the pieces to be applied to the shoe upper parts represented by the paper patterns.

In order to determine the proper location of 75

the quarters 10 and the stacks 11 on the patterns 13 and 18, respectively, these patterns, without anything on their exposed surfaces, are placed in position on the beds 16 and 21, respectively. 5 With the head 62 positioned at the pick-up station, as shown in Figs. 1 and 2, the handle 68 is pressed downwardly to force the dies 54 and 55 into contact with the pattern 18 to imprint, through carbon paper or otherwise, their contour on the surface of the pattern 18. These imprints are used as guides to determine the location of the eyelets 22 for the pins 23 which confine laterally the pieces 12 in the stacks 11 in all directions by engagement with various points on 10 their edges.

Then the handle 68 is elevated into the position of Fig. 4 and the head 62 is slid to the left (Fig. 1) to bring the left side end thereof in contact with a buffer 77 (Figs. 1 and 2) as shown in Fig. 2. 15 When the head 62 is in contact with the buffer 77 the pin 74 is registered with a hole 78 in the horizontal rod 63 thus permitting the rod 63 to be reciprocated to bring the dies 54 and 55 into engagement with the exposed surface of the pattern 13 and print or impress their contours thereon.

Then the paper patterns, hereinbefore referred to, are placed upon the pattern 13 and the edges of the openings in the paper patterns are registered with the imprints of the dies 54 and 55. 20 Next lines are scribed on the pattern 13 employing the available gaging edges of the registered paper patterns as guides. These available edges may be held to a grade. The scribed lines are used to determine the location of the gages 79 and 80, of the bumper type, on the pattern 13.

As indicated in Fig. 1 portions of the stays 12 register with edges on the quarters. In many instances, however, the overlays, underlays or 25 reinforces generally are located within the marginal portions of the shoe upper parts supported on the pattern 13. Thus, the gages 79 and 80 gage the location of the shoe upper parts on the pattern 13 relatively to the dies 54 and 55 so that any predetermined portion of the superficial surface of the said shoe upper parts may receive the pieces 12. It will be clear, viewing Fig. 4, that if the rod 60 is reciprocated to lower the dies 54 and 55 while the pin 74 is not in a 30 position to enter the openings 72 or 78, the pin will strike the rod 63 and so block further descent of the dies. In this manner superimposing accuracy is assured because the operation of the pin 74 in the openings 72 and 78 necessitates first 35 that the pieces 12 register accurately with the dies 54 and 55 and then that the pieces 12 be superimposed upon only the predetermined portion of the superficial surface of the shoe upper parts 10.

The gages 79 and 80 gage a complete series of shoe upper parts of the same style, one pair at a time, in position to receive in a uniform manner the pieces 12 which, however, are not graded in any way, they being the same size for all the 40 various sizes and widths in the complete series of shoe upper parts supported upon the pattern 13.

In order to enable the dies 54 and 55 to pick up the uppermost pieces in the stacks 11 and 45 retain them in position while the pieces are being transferred to and superimposed upon the quarters 10, the bottom faces of the dies 54 and 55 are provided with vertical air passages 81 and 82, respectively, (Fig. 2). The upper ends of these air passages 81 and 82 receive hollow ferrules 83 and 84, respectively, carried by flexible 50

conduits 35 and 36 communicating with a header 37. In addition to the conduits 35 and 36, the header 37 is connected to two more suction conduits 38 and 39. These conduits are not used with small dies like the dies 54 and 55, but the ferrules on the lower ends thereof are fitted into blind openings 90 and 91 formed in the head 62. 5

The header 37 communicates with one end of a flexible conduit 92 (Fig. 1) the other end of which is connected with the intake of an air pump 93 10 mounted on the bed plate 17 and driven by the armature shaft 94 of an electric motor 95. When the air pump 93 is in operation air is drawn through the openings 81 and 82 thus producing a condition of unbalanced pressure on the bottom faces of the dies 54 and 55 which causes the uppermost pieces on the stacks to adhere to the dies when they are engaged therewith. The air drawn into the pump 93 is discharged through an outlet 96. The suction pull on the 15 pieces engaged by the dies may be varied by a petcock 97 interposed in the suction line between the conduit 92 and the inlet to the pump 93.

The pieces 12 used for overlays, underlays, and 20 reinforces generally, may be of three general types, namely, thermoplastic, hydroplastic, or dry. By thermoplastic I mean that the face of the piece which is to engage the shoe upper part is coated with an adhesive normally non-adhesive under ordinary conditions of temperature but which is capable of being rendered tacky by the application of heat thereto. By hydroplastic I mean that the coating requires the application of water thereto in order to render it adhesive. By dry I mean that the bottom face 25 of the piece is uncoated and is rendered adhesive by the application of some sticky material such as latex, gum, paste, cement or the like.

If the pieces are hydro-plastic the machine is 30 provided with a cylindrical roller 98 (Figs. 1, 2, 7 and 8) constructed of some moisture absorbent material, such as sponge rubber 99. The sponge rubber 99 is mounted on a core 100 which in turn is mounted on a shaft 101 having ends journaled on the bottoms of slots 102 formed on the 35 end flanges 103 (Fig. 1) of a small tank 104. The tank 104 is removably mounted within a holder 105 which in turn is removably mounted on the bed plate 17 in the space between the beds 16 and 21. The holder 105 (Fig. 1) is provided 40 with an outturned end flange 106 having a slot 107 therein which receives a pin 108, on the bed plate 17, to the upper end of which is threaded a butterfly nut 109 for clamping the flange 106 to the bed plate 17. The holder 105 is provided also 45 with a slotted end flange 110 (Fig. 2) which fits over a pin 111, on the bed plate 17, for engagement with a butterfly clamping nut 112.

When the dies 54 and 55 are moved into engagement with the uppermost hydroplastic pieces 50 on the stacks 11, respectively, the suction produced by the air pump 93 causes the pieces to adhere to the dies and to leave the stacks upon the return of the dies to the position of Fig. 4. Then the head 62 is reciprocated to the left (Figs. 65 1 and 2) to bring the picked-up pieces into the superimposing position of Fig. 3. As the dies move from the position of Fig. 1 to that of Fig. 3 the pieces wipe over the periphery of the roll 68 and the hydroplastic coating on the pieces is rendered 60 adhesive by the water on the roll. During the engagement of the pieces with the roll 68 the suction holds the pieces from displacement on the dies.

After the head 62 is positioned as shown in Fig. 75

3, the dies are reciprocated to superimpose the sticky pieces upon the shoe upper parts supported upon the pattern 13. The pieces engage the underlying shoe upper parts with sufficient pressure to cause the pieces to adhere substantially instantly thereto. As soon as the handle 63 is released the dies are elevated but the pieces are not carried upwardly by the dies, the adherence of the pieces to the shoe upper parts being sufficient to break the suctional grip of the dies on the pieces.

In order to prevent the roll 98 from wetting the bottom faces of the dies as they return to obtain another pair of pieces from the stacks 11 for application to another pair of shoe upper parts positioned in the pattern 13, the machine is provided with mechanism for lowering the roll 98 to withdraw its periphery from the plane of reciprocation of the dies. To this end 20 the end flanges 106 and 110 of the holder 105 support for rotation a horizontal shaft 113 through which are threaded screws 114 (Figs. 7 and 8). When the dies are travelling from the pick-up station to the superimposing station the tank 104 is supported upon the heads of the screws 114 (Fig. 7). When the dies are travelling back to the pick-up station the bottom of the tank 104 rests upon the shaft 113 (Fig. 8).

In order to oscillate the shaft 113 in timed relation with the horizontal movements of the dies 30 the rear end of the shaft 113 carries an arm 115 which is secured to the shaft by a screw 116. The movement of the shaft 113, in a clockwise direction viewing Fig. 7, is limited by a stop pin 35 117 projecting rearwardly from the rear flange 106 of the holder 105. This stop pin insures the uniform elevation of the roll 98 to bring its periphery into the horizontal plane of movement of the dies.

40 The arm 115 is provided with a slot 118 which embraces a pin 119 projecting laterally from a slide 120. The slide 120 is provided with slots 121 (Fig. 2) which embrace the shanks of small headed bolts 122 (Fig. 1) secured to brackets 123 (Fig. 3) secured respectively to the beds 16 and 21. At its opposite ends the slide 120 is provided with upstanding lugs 124 and 125 (Fig. 2) arranged in the path of movement of a pin 126 (Fig. 4) projecting laterally from an arm 127 depending from the head 62. When the head 62 is reciprocated into the position of Fig. 3 to bring the dies into the superimposing station the pin 126 strikes the lug 124 and moves the slide to the left (Figs. 1 and 2) thereby oscillating, 50 through the connections described, the shaft 113 into the position of Fig. 8. When the head 62 is reciprocated back into the position of Fig. 1 the pin 126 strikes the lug 125 and moves the slide 120 to the right (Figs. 1 and 2) thereby oscillating the shaft 113 into the position of Fig. 7. Thus the roll 98 is elevated for the passage of the dies thereover from the pick-up station to the superimposing station, and is lowered for the return of the dies to the pick-up station.

65 When the head 62 is moved back into the pick-up station another pair of shoe upper parts is placed on the pattern 13 against the gages 79 and 80 and the cycle of operations is repeated. As described hereinbefore the pins 23 by engagement with the plate 56 limit the downward movement of the dies. After one piece has been removed from each of the stacks it is necessary to lower the plate 26 a distance commensurate with the thickness of the removed pieces so that the 70 upper ends of the pins 23 may be maintained a

uniform distance above the uppermost pieces in the stacks until all the pieces are removed therefrom.

In order to control the lowering of the pins 23 automatically the arm 47 is provided with a lug 128 which is engaged by a toe 129 formed on the lower end of the arm 127. Each time the head 62 is returned to the pick-up station the toe 129 strikes the lug 128 and oscillates the arm 47 to rotate the ratchet 41 and the verge 40. As 10 the verge 40 rotates, the roll 39 is moved to the right (Fig. 4) and the plate 26 is lowered an amount commensurate with the thickness of the pieces in the stacks. As this thickness may vary with the different types of work pieces handled, the lug 128 is secured to one end of a screw 130 threaded into the upper end of the arm 47, the adjustment of the screw 130 being maintained by a winged clamping nut 131. From an inspection of Fig. 9 it will be understood that 20 the earlier the toe 129 engages the lug 128 in the return of the head 62 to the pick-up station the greater will be the rotative movement of the ratchet 41 and the consequent greater distance through which the plate 26 is lowered. The 25 peripheral edge of the verge 40 is shaped to permit the roll 39 to escape along a lateral wall 132 (Fig. 4), under the influence of the springs 45, when the pieces are all withdrawn from the stacks. Thus, the pins 23 are caused to pop up 30 through the eyelets 28 into their original positions ready to receive two more stacks of pieces 12 immediately upon the exhaustion of the stacks.

If the pieces in the stacks are the dry type 35 hereinbefore referred to, the tank 104 is supplied with the adhesive and the roll 98, or a substitute therefor, is then used to apply the adhesive to the bottom faces of the dry pieces as they are dragged across the periphery of the 40 roll by the dies.

If the pieces in the stacks are thermoplastic, the die holder 57 is provided with an electrical heating unit, (not shown), the terminals 133 and 134 (Fig. 1) thereof being connected to some 45 suitable source of electricity.

But whether the pieces in the stacks are thermoplastic, hydroplastic or dry, they are rendered adhesive during the travel of the dies from the pick-up station to the superimposing station. 50 The roll 98, the tank 104, or, it may be, the holder 105 therefor, may be removed from the machine during its use on thermoplastic pieces.

It is often desirable in the manufacture of shoes to apply a doubler to a shoe upper part. 55 Usually the doubler and the shoe upper part are the same size and shape so that it is necessary to register their edges in assembling them together. Owing to the porous character of the material from which the doubler is made it would 60 be impracticable to employ suction means for transferring the doubler from the pick-up station to the superimposing station. Therefore, in assembling a doubler and a shoe upper part together the doublers are supported, one at a time, 65 on a pattern 135 (Fig. 5) while a stack of shoe upper parts are supported on the pattern 18.

Owing to the grade of the doubler it is not practicable to employ gages of the bumper type like the gages 79 and 80, Fig. 1. Instead, the 70 pattern 135 (Fig. 5) is provided with a line gage 136, with which certain edges on the doubler are registered. To this end the pattern 135 may be, and preferably is, the attachment illustrated in Fig. 4 of the drawings in my Patent No. 75

1,881,399, October 4, 1932. The pattern 18 supports a stack of shoe upper parts 137 (Fig. 5) having the same shape and superficial area as the doubler. These shoe upper parts 137 are 5 engaged by the pins 23 to form the stack.

When using the machine to pick-up the shoe upper parts 137 from the stack on the pattern 18 a flat die 138 is secured to the holder 57 by means of the latches 59 which engage the vertical pins

10 58 projecting from the back face of the die 138. The die 138 is provided with a number of air passages 139, any selected four of which may be connected to the four conduits 85, 86, 88 and 89.

15 After the die 138 picks up the shoe upper part it is transferred to the superimposing station where the shoe upper part is superimposed upon the doubler. In between the stations the shoe upper part is rendered adhesive in the manner hereinbefore described with reference to the 20 pieces 12.

Nothing herein explained is to be interpreted as limiting the various inventions in the scope of their application to use in connection with the particular apparatus or the particular 25 mode of operation or both selected for purposes of illustration and explanation. While the particulars of construction herein set forth are well suited to one mechanical form of the invention, it is not limited to these details of 30 construction, nor to the conjoint use of all its features, nor is it to be understood that these particulars are essential since they may be modified within the skill of the artisan without departing from the true scope of the actual 35 inventions, characterizing features of which are set forth in the following claims by the intentional use of generic terms and expressions inclusive of various modifications.

What is claimed as new, is:

40 1. In an assembling machine, the combination with means for supporting separately the parts to be assembled, of means having continuous suction for assembling the parts.

45 2. In an assembling machine, the combination with means for supporting separately the parts to be assembled, of heated means having continuous suction for assembling the parts.

50 3. In a machine for assembling parts one face of at least one of which is thermoplastic, the combination with means for supporting separately the parts to be assembled, a die for engagement with the non-thermoplastic face of the thermoplastic part, means for heating the die, and suction means connected to the die, of means 55 for operating the die to pick up the thermoplastic part, render it adhesive, superimpose the adhesive thermoplastic part upon the other part and subject the assembled parts to pressure.

55 4. In an assembling machine, the combination with removable patterns, and means for locating thereon the parts to be assembled, respectively, of means for picking up at least one part from one of the patterns and superimposing it in a pre-determined position upon a part located on another pattern.

60 5. In an assembling machine, the combination with a support for a pair of shoe upper parts, one right and one left, and a support for two piles of pieces of stock, of means for picking up two 65 pieces, one from each pile, and superimposing them upon the right and left shoe upper parts, respectively, mounted on their original support.

65 6. In an assembling machine, the combination with means for supporting separately the parts 70 to be assembled, reciprocating mechanism for

75 picking up at least one part and superimposing it upon another part on another original support, movable overhead means adapted to receive said reciprocating mechanism, and means for limiting the movement of said overhead means, of means operating independently of said movement limiting means for constraining the pick-up movement of said reciprocating mechanism to a perpendicular.

7. In an assembling machine, the combination 10 with means for supporting separately the parts to be assembled, reciprocating mechanism for picking up at least one part and superimposing it upon another part on another original support, movable overhead means adapted to receive 15 said reciprocating mechanism, and means for limiting the movement of said overhead means, of means operating independently of said movement limiting means for constraining both the picking up and the superimposing movements of 20 said mechanism to perpendiculars.

8. In an assembling machine, the combination 25 with means for supporting separately the parts to be assembled, reciprocating mechanism for picking up at least one part and superimposing it 30 upon another part on another original support, movable overhead means adapted to receive said reciprocating mechanism, and means for limiting the movement of said overhead means, of means operating independently of said movement limiting means for constraining the pick-up and superimposing movements of said reciprocating mechanism to rectilinear movements in vertical planes.

9. In an assembling machine, the combination 35 with means for supporting separately the parts to be assembled, reciprocating mechanism for picking up one part and superimposing it upon another part, movable overhead means adapted to receive said reciprocating mechanism, means 40 for limiting the movement of said overhead means, and means operating independently of said movement limiting means for constraining the pick-up and superimposing movements of said reciprocating mechanism to rectilinear movements in vertical planes, of means underlying 45 said reciprocating mechanism during the operation of said constraining means for correlating an identical superficial area on said parts uniformly with relation to said vertical planes, 50 respectively.

10. In an assembling machine, the combination with a support for a plurality of shoe upper parts and a support for a plurality of piles of pieces of stock, of means for picking up pieces, 55 one from each pile, and superimposing them upon the shoe upper parts, respectively, mounted on their original support.

11. In a coating machine, the combination with a roll, of suction means movable in one plane for 60 picking up small, thin work pieces and movable in a different plane for drawing the pieces in a rectilinear path from a position on one side of the roll across the periphery of the roll to the other side thereof, and means operatively connected to the suction means for elevating the roll for the drawing movement of the suction means.

12. In a stock-handling machine, the combination with a support for a stack of pieces of 70 stock and a plurality of members associated with said support to confine the pieces laterally in all directions by engagement with various points on their edges, of mechanism having a face engageable with said members and a face insertable 75

- within the area bounded by the members for withdrawing the pieces one at a time from the stack.
13. In a stock-handling machine, the combination with a support for a stack of pieces of stock and a plurality of members loosely mounted in said support to confine the pieces laterally in all directions by engagement with various points on their edges, of a support for the lower ends of said members. 5
14. In a stock-handling machine, the combination with a support for a stack of pieces of stock and a plurality of members loosely mounted in said support to confine the pieces laterally in all directions by engagement with various points on their edges and a support for the lower ends of said members, of means for lowering the second named support intermittently. 10
15. In a stock-handling machine, the combination with a support for a stack of pieces of stock and a plurality of members loosely mounted in said support to confine the pieces laterally in all directions by engagement with various points on their edges and a support for the lower ends of said members, of means for lowering the second named support intermittently a distance substantially commensurate with the thickness of one of the pieces. 15
16. In a stock-handling machine, the combination with a box having a removable cover provided with a plurality of openings and a false bottom, of a plurality of pins loosely mounted in the openings and engaged with the false bottom. 20
17. In a stock-handling machine, the combination with a box having a removable cover provided with a plurality of openings and a false bottom, and a plurality of pins loosely mounted in the openings and engaged with the false bottom, of means for raising and lowering the false bottom. 25
18. In a stock handling machine, the combination with a stationary support for a stack of pieces of stock, vertically movable means for confining the stacked pieces laterally in all directions by engagement with various points on their edges, and means for imparting movement to said confining means, of means for maintaining said confining means in a given position to which it is moved by said movement imparting means 30 until moved thereby to a different position. 30
19. In a stock-handling machine, the combination with a diminishable magazine having a stationary bottom and an open top for holding a stack of pieces of stock, and mechanism for withdrawing the pieces one at a time through the open top of the magazine and for diminishing the magazine with each withdrawal, of means for maintaining the magazine in the diminished state resulting from one withdrawal until the magazine is further diminished as the result of a subsequent withdrawal. 35
20. In a stock-handling machine, the combination with a diminishable magazine having a stationary bottom and an open top for holding a stack of pieces of stock, and mechanism having a face engageable with said magazine for withdrawing the pieces one at a time out through its open top and for diminishing the magazine with each withdrawal, of means for maintaining the magazine in the diminished state resulting from one withdrawal until the magazine is further diminished as the result of a subsequent withdrawal. 40
21. In a stock-handling machine, the combination with a magazine having a stationary bottom and an open top for holding a stack of pieces of stock, of mechanism having a face engageable with said magazine and a face shaped similar to the exposed face of the uppermost piece in the stack insertable within said open top for withdrawing the pieces one at a time from the stack. 45
22. In a stock-handling machine, the combination with a magazine having a stationary bottom and an open top for holding a stack of pieces of stock, of mechanism for withdrawing the pieces one at a time from the magazine and shortening the height of the stack retaining wall of the magazine a distance substantially commensurate with the thickness of one of the pieces in the stack. 50
23. In a stock-handling machine, the combination with a support for a stack of pieces of stock and a retaining wall therefor, of mechanism having a face shaped similar to the exposed face of the uppermost blank in the stack insertable within the area bounded by the retaining wall for withdrawing the pieces one at a time from the stack. 55
24. In a stock handling machine, the combination with a stationary support for a stack of pieces of stock, a vertically movable retaining wall therefor, and reciprocating means for imparting movement to said wall, of means engaging the wall for maintaining it in a given position to which it is moved by said reciprocating means until moved thereby to a different position. 60
25. In a stock handling machine, the combination with a stationary support for a stack of pieces of stock, means for removing the pieces from the stack one at a time, and means, movable vertically by engagement with the removing means, for confining the stacked pieces laterally in all directions by engagement with various points on their edges, of means for maintaining the confining means in a given position to which it is moved by the removing means until moved thereby to a different position. 65
26. In a stock handling machine, the combination with a stationary support for a stack of pieces of stock, means for removing the pieces from the stack, one at a time, and a retaining wall for the stack, said wall being vertically movable by the engagement of the removing means therewith, of means for maintaining the wall in a given position to which it is moved by the removing means until moved thereby to a different position. 70
27. In an assembling machine, the combination with removable patterns, means for locating thereon the parts to be assembled, respectively, and means for picking up at least one part from one of the patterns and superimposing it upon a predetermined portion of a part located upon another pattern, of means for blocking any superimposing movement of said first named means other than that causing superimposition of a part from one pattern upon said predetermined portion of a part on said other pattern. 75
28. In an assembling machine, the combination with a support for a plurality of shoe upper parts, a support for a plurality of piles of pieces of stock, and means for picking up pieces, one from each pile, and superimposing them upon the shoe upper parts, respectively, mounted on their original support, of means for blocking any superimposing movement of the first named means other than that causing superimposition of said pieces upon a predetermined portion of said shoe upper parts, respectively. 80
